WRINGER

George W. Wardwell, Jr., Nichols, and James I. Arnett, Stratford, Conn., assignors to General Electric Company, a corporation of New York

Application July 18, 1939, Serial No. 285,103

3 Claims. (Cl. 68—262)

The present invention relates to clothes wringers of the type in which the pressure between the rolls is released when the wringer is not in operative condition and in which the wringer is placed in operative condition by movement of a control bar which presses the rolls together. The control bar may also control the wringer driving mechanism to start rotation of the rolls when pressed together and to stop the rotation 10 of the rolls when the pressure is released.

The object of our invention is to provide an improved construction and arrangement in wringers of this type, and in particular to provide a construction in which the control bar is prevented from jumping out of the wringer frame 15 when the wringer is released.

For a consideration of what we believe novel and our invention, attention is directed to the following description and the claims appended thereto.

In the accompanying drawing, Fig. 1 is a side elevation partly broken away of a wringer embodying our invention; Fig. 2 is an enlarged sectional elevation of one end of the wringer; Fig. 25 3 is a top plan view of the plate containing the cam slot used for shifting the driving gears for the wringer; Fig. 4 is an end view, partly broken away, the wringer being in the inoperative condition in which the pressure between the wringer 30 rolls is released; Fig. 5 is a view similar to Fig. 4, the wringer being in the operative condition in which the wringer rolls are pressed together; Fig. 6 is a fragmentary perspective view of one end 35 of the control bar; and Fig. 7 is a perspective view of one of the spring pressed members for pressing the upper roll against the lower roll.

Referring to the drawing, there is shown a wringer having a frame comprising side stiles 1 and 2. The side stile 1 is fixed to a wringer head 3 having a depending tubular portion 4 for pivotally supporting the wringer on the wringer post 5 of a domestic washing machine. The bottom member of the wringer frame comprises a bar 3a bolted to the wringer head and to the side stile 2. The outer end of the side stile 2 is covered by a plate 6 suitably fixed thereto. The tubular portion 4 of the wringer head is provided with a spring pressed detent 7 which is adapted to fit in any one of a series of spaced openings 8 in a collar 9 fixed to the wringer post to lock the wringer in a fixed angular position with respect to the wringer post.

Through the wringer post extends a wringer drive shaft 10 which is continuously rotated, for example by the mechanism (not shown)

used to drive the washing machine. The shaft 10 projects beyond the upper end of the wringer post 5, and on its projecting end is fixed a pinion 11 which is adapted to mesh selectively with one or the other of a pair of crown gears 12. The crown gears are welded to a sleeve 13 which is slidably splined on a horizontal shaft 14. The left-hand end of shaft 14 is journaled in a bearing 15 carried in a boss 16 on the wringer head 3. The right-hand end of the shaft 14 has fixed 10 thereto a coupling member 17 which rotates in a bearing 18 in a boss 19 on the side stile 1 and serves as a support for this end of the shaft 14. The gears 12 are shifted by a yoke 20 which fits over the gears and is pivoted at its left end on 15 the boss 16 and at its right end on the shaft 14. Thrust washers 21 are arranged between the inner faces of the yoke 20 and the outer faces of the gears 12. On the upper side of the yoke 20 is fixed a plate 22 (Fig. 3) having a cam slot 23 20 therein which cooperates with a pin 24 threaded into the top wall of the wringer head. With this construction it is obvious that as the yoke 20 is pivoted on the shaft 14 the pin 24 will cooperate with the cam slot 23 to move the yoke 20 to the 25 right or left so that one or the other of the gears 12 will mesh with the driving pinion 11, thus controlling the rotation of the shaft 14. When the driving pinion 11 meshes with one of the gears 12 the pin 24 rests in one of the portions 30: 25 of the cam slot 23.

The lower and upper wringer rolls 26 and 27 are carried between the side stiles 1 and 2. The lower wringer roll 26 is fixed to a shaft 28 the right end of which is rotatably carried in a bearing 29 in a roll guard 30 which is pivoted in an arcuate portion 31 in the side stile 2. At the left end of the rolls is another roll guard 32 which is pivoted on the boss 19. Both roll guards have inwardly extending flanges 33 which overlap 40: the ends of the wringer rolls and keep the clothes from passing beyond the ends of the rolls. The left end of the shaft 28 terminates in a coupling 34 having a pin 35 fixed therein, the projecting ends of which extend within cooperat- 45: ing slots in the coupling member 17. The left end of the shaft 28 is supported by a cylindrical portion 36 of the coupling 34 which extends within a depression 37 in the coupling member 17.

The upper wringer roll 27 is rotatably carried on a shaft 38 fixed at each end to vertically extending arms 39 which are connected at their upper ends by a control bar 40 which extends across the top of the wringer. The assembly 55

comprising the control bar 40, the arms 39, and the shaft 38 serves as a carrier for the upper roll 27. The arms 39 are provided with bosses 41 which fit in open ended slots 42 in the pivoted roll guards 30 and 32. Above the bosses 41 are pins 43 which are pressed into the outer faces of the arms 39. Below the pins 43 are the reduced projecting ends 44 of the shaft 38. The projections 43 and 44 are loosely receivable in vertical slots 45 in pressure members or receivers 46. As shown in Fig. 4, the pressure members are slidably carried in the side stiles 1 and 2 and are urged downward against bosses or shoulders 47 on the side stiles by coil springs 50 surrounding bolts 48 extending up through the bosses 47 in the side stiles and threaded into bosses 49 on the pressure members. The coil springs 50 are arranged between the under side of the bosses 47 and the heads of the bolts. The lower position of the pressure members 46 is adjusted by washers 51 arranged between the upper side of the shoulders 47 and the lower side of the bosses 49. The upper position of the pressure members is limited by the tension of the springs 50. The upper ends of the pressure members are guided by guides 52 at the top of the side stiles 1 and 2.

When the upper roll and control bar are in the position shown in Fig. 4 the pressure between the rolls is released since the control bar and upper roll are free to move upward in the slots or recesses 45 in the pressure members 46. In this position the bosses 41 cooperate with the slots 42 in the roll guards 30 and 32 to move the roll guards to a central position. The roll guard 32 now cooperates with the yoke 20 to maintain both of the gears 12 spaced from the driving pinion 11, as shown in Fig. 1. Therefore, the rotation of the rolls is stopped in addition to the roll pressure being released.

To apply the roll pressure and to start the rotation of the rolls, the control bar 40 is pulled toward the operator to the inclined position shown in Fig. 5. In moving toward this position the pins 43 engage rollers 53 which are rotatably carried on opposite sides of the recess 45 on pins 54 fixed at each end to spaced walls 55 in the pressure members 46. The spaced walls 55 provide a recess for receiving the rollers 53, as is shown more clearly in Fig. 7. Upon engagement of the pins 43 with the rollers 53 on one side of the recesses 45, the pins 43 serve as a fulcrum, about which the control bar pivots. The pivotal movement of the control bar causes the projections 44 at the lower ends of the arms 39 to be forced under rollers 56, as is shown in Fig. 5. The rollers 56 are likewise located on opposite sides of the recess 45 and are rotatably carried in the recess between the spaced walls 55 on pins 57 fixed at opposite ends in the walls 55. The rollers 56 serve as cam surfaces for fixing the upper roll to the pressure members 46. When the projections 44 are forced or wedged under the rollers 56, the pressure members 46 are slightly raised above the washers 51, as shown in Fig. 7, compressing the coil springs 50 and applying pressure between the wringer rolls. The force exerted on the upper wringer roll acts in the direction of the arrow 58 (Fig. 5). This force therefore tends to maintain the projections 44 under the rollers 56. In this position flat surfaces 59 at the lower ends of the arms 39 rest against flat surfaces 60 on the pressure members 46. These surfaces cooperate to limit the movement of the projections 44 under the rollers 56.

In the course of the movement of the projections 44 under the rollers 56 the pressure exerted on the upper roll 27 opposes the movement until the center line of the projection 44 reaches a center line connecting the roller 56 and the lower wringer roll 26. After this point is reached the force exerted on the upper roll by the lower roll aids the movement of the projections 44 under the rollers 56, and when the final position is reached, as shown in Fig. 5, this pressure holds the projections under the rollers. At this time the pins 43 are out of contact with the rollers 53 and are not effective in maintaining the pressure between the rolls.

As the control bar 40 is moved to the inclined position shown in Fig. 5, the bosses 41 at the lower ends of the arms 39 cooperate with the open ended slots 42 in the roll guards 30 and 32 to tilt the roll guards as indicated in Fig. 5. This tilting movement of the roll guard 32 is transmitted to the yoke 20 by means of a tongue 61 on the yoke which fits in a groove 62 in the roll guard 32 and, as explained above, causes the yoke to be moved axially along the shaft 14 due to the cooperation of the pin 24 and the cam slot 23. This moves one or the other of the gears 12 into mesh with the driving pinion 11 and starts the rotation of the lower roll. The gearing is arranged so that when the control bar 40 is pulled toward the operator, the rolls are rotated in the direction to feed clothes away from the operator.

When the parts are in the position shown in Fig. 5, the lower roll is, as described above, rotated in the direction of the arrow 61. The torque exerted on the upper roll by the lower roll accordingly tends to hold the projections 44 under the rollers 56.

The pressure between the rolls is released and the rotation of the rolls is stopped by returning the control bar 40 to the central or vertical position. This means that the upper end of the control bar 40 is moved to the left as viewed in Fig. 5. Since the pins 43 are out of contact with the rollers 53 the control bar pivots about the projections 44 at the start of this movement. The flat surfaces 59 at the lower ends of the arms 39 cooperate with the surfaces 60 on the pressure members 46 to pry the projections 44 from under the rollers 56. Since the point of contact between the surfaces 59 and 60 is very close to the center of the projections 44, a large leverage is obtained to assist the prying action. When the projections 44 move to the right (Fig. 5) of a center line connecting the lower roll and the rollers 56, the roll pressure begins to assist in moving the projections 44 from under the rollers 56. Since the roll pressure is large compared to the force exerted by the operator on the control bar, the additional movement of the control bar from this position to the central position of Fig. 4 is easily effected. The pins 43 are moved clear of the rollers 53 before the projections 44 are released from the rollers 56. The rollers 53 and projections 43 have substantially no action during the pressure release. There may be a momentary contact between the projections 43 and rollers 53.

Upon the return of the control bar to the central position the rotation of the rolls is stopped and the roll pressure is released. The wringer is accordingly in an inoperative condition.

With the above described construction it is apparent that the roll pressure is applied easily and, due to the prying action obtained by the cooperating surfaces 59 and 60, is still more easily released. This is important because under emergency conditions the operator may be required to move the control bar 40 to the inclined position to release the pressure between the rolls.

gency conditions when it is desired to release the roll pressure quickly, the rolls are usually separated, and accordingly the roll pressure is greater due to the greater compression of the springs 58. 5 In the present construction the leverage effective for applying the pressure is that obtained by using the pins 43 as fulcrum points. The leverage for releasing the pressure is that obtained by using the points of contact between the surfaces 59 and 60 as fulcrum points. It is therefore obvious that 10 the leverage is greatly increased for the pressure releasing movement of the control bar.

When the control bar is in the central position, as shown in Figs. 1, 2, and 4, it is free to move upward in the slots 45 in the pressure members 46. Since just prior to reaching this position the control bar was subjected to the full pressure between the rolls, this pressure is effective to move the control bar upward. Unless restrained, the 20 control bar might jump out of the wringer. In the present construction this is prevented by walls 68 at the upper ends of the pressure members 46, which close the upper ends of the walls 45 and cooperate with the projections 43 to limit the 25 upward movement of the control bar. The walls 68 which limit the upward movement of the control bar would, in the absence of other provisions, prevent the removal of the control bar and upper roll, which is desirable to permit easy 30 cleaning of the wringer. To provide for removal of the control bar, one of the pressure members 46 is provided with a slot or recess 69 at the upper end into which the projections 43 and 44 may be moved by endwise movement of the control 35 bar, as shown in Fig. 1. In this position the projections 43 and 44 at the other end of the control bar are clear of the wall 68 in the adjacent pressure member 46, and the control bar can accordingly be pivoted about the projections 40 within the slot 69 to move the other end of the control bar clear of its pressure member. Since the removal of the control bar is possible only upon endwise movement, there is no danger of the control bar jumping out of the wringer upon 45 release of the pressure. This is further prevented by the fact that the endwise movement is possible only when the control bar is in a vertical position so that both projections 43 and 44 are in alignment with the slot 69. Also, when 50 the projections at one end of the control bar are in the slot 69, the projections at the other end of the wringer must be moved upward through a notch 70. If the projections are out of alignment with either the slot 69 or the notch 70, it 55 is impossible to remove the control bar. It is therefore apparent that by the present construction the control bar is at all times held in

the wringer unless the operator intends to remove the same.

What we claim as new and desire to secure by Letters Patent of the United States is:

1. In a wringer, a frame consisting of spaced side stiles and a bottom frame member, a lower roll carried in the frame, a control bar extending across the top of the wringer carrying an upper roll, pressure members in the side stiles, vertical passages slidably receiving the control bar in a central position, means effective upon tilting the control bar to lock the control bar to said pressure members, walls at the upper ends of said passages for retaining the control bar therein, and a recess in one of said passages for receiving one end of the control bar upon endwise movement thereof whereby the control bar may be tilted about said recess to move the other end of the control bar clear of the wringer. 5

2. In a wringer, a frame consisting of spaced side stiles and a bottom frame member, a lower roll carried in the frame, a control bar extending across the top of the wringer carrying an upper roll and having projections at each end, pressure members in the side stiles, vertical passages in said pressure members slidably receiving said projections, cam surfaces on the pressure members, means effective upon tilting of the control bar for forcing said projections under said cam surface to lock the control bar to said pressure members, walls at the upper ends of said passages cooperating with said projections to retain the control bar therein, and a recess in one of said passages for receiving the projections at one end of the control bar upon endwise movement thereof whereby the control bar may be tilted to move the projections at the other end thereof clear of its pressure member. 20 25 30 35

3. In a wringer, a frame consisting of spaced side stiles and a bottom frame member, a lower roll carried in the frame, a control bar extending across the top of the wringer carrying an upper roll and having projections at each end, pressure members in the side stiles, walls on said pressure members defining vertical passages slidably receiving said projections, said walls cooperating with the projections to prevent removal of the projections from the passages by vertical or lateral movement of the control bar, means for releasably locking the control bar to the pressure members, and a recess in one of said passages for receiving the projections at one end of the control bar upon endwise movement thereof whereby the control bar may be tilted about said recess to move the other end of the control bar clear of its passage. 40 45 50 55
